R. M. GILSON

RAILWAY TRAFFIC CONTROLLING APPARATUS

Original Filed Aug. 19, 1924

UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY TRAFFIC CONTROLLING APPARATUS.

Original application filed August 19, 1924, Serial No. 732,927, now Patent No. 1,631,808, dated June 7, 1927. Divided and this application filed May 6, 1927. Serial No. 189,258.

My invention relates to railway traffic controlling apparatus, and particularly to apparatus comprising train carried governing mechanism controlled by energy received from the trackway. More particularly my present invention relates to the trackway portion of such apparatus.

5

The present case is a division of my pending application Serial No. 732,927 filed 10 August 19, 1924, for railway traffic controlling apparatus, which has matured into Patent No. 1,631,808, dated June 7, 1927.

I will describe one form of trackway apparatus embodying my invention, and will 15 then point out the novel features thereof in claims.

The accompanying drawing is a diagrammatic view illustrating one form of trackway apparatus embodying my invention.

20 Referring to the drawing, the reference characters 2 and 2^a designate the track rails of a stretch of railway track over which traffic moves in both directions. These rails are divided, by means of insulated joints 3, 25 into a plurality of successive track sections A—B, B—C, etc. The stretch of track shown in the drawing is intended for use in a railway system having electric propulsion, and for this reason impedance bonds 14 of 30 the usual and well known form are provided at the junction of each two adjacent track sections for the purpose of conducting propulsion current around the insulated joints 3.

35 Means are provided for at times supplying each track section with alternating currents of different characteristics. As here shown the alternating currents are of different frequencies. A transmission line comprising 40 two line wires 13 and 13^a is supplied with alternating current of one frequency from a suitable source such as an alternator K, and a second transmission line comprising two line wires 12 and 12^a is constantly supplied 45 with alternating current of a different frequency from a suitable source such as an alternator J. Current supplied from line wires 13 and 13^a is used to control train carried governing mechanism of a suitable type, 50 and I shall hereinafter call such current the "train governing current." Alternating current supplied to the trackway from line

wires 12 and 12^a is used to control trackway apparatus, and I shall hereinafter term such current the "track circuit current". 55 The train governing current is preferably, though not necessarily, of higher frequency than the track circuit current.

Each track section is provided with two track relays each designated by the reference character R with a suitable distinguishing exponent and one located at each end of the section. Each track relay comprises two windings 10 and 11, one of which winding 10, is constantly supplied with alternating 60 current from line wires 12 and 12^a. Track circuit current is supplied to each track section, as will appear hereinafter, from two track transformers, each designated by the reference character T with an appropriate 65 exponent. One such track transformer is located adjacent each end of each section and has a secondary winding 5 constantly connected through an impedance 6 across the rails of the section. A train governing 70 transformer is located adjacent each end of each section and has a secondary winding 8 constantly connected through an impedance 9 with the rails of the section. Each such train governing transformer is designated 75 by the reference character S with a suitable distinguishing exponent. Associated with each track relay R is a line relay designated by the reference character H with a distinguishing exponent. These line relays are 80 controlled in accordance with the usual practice in absolute permissive block signaling 85 systems, and since the control of these relays forms no part of my present invention I have omitted the circuits from the drawing for 90 the sake of simplicity. For example, one form of apparatus embodying line relays controlled in this manner is disclosed in Letters Patent of the United States, No. 1,602,137, granted to H. A. Wallace on October 5, 1926, for railway traffic controlling 95 apparatus. For purposes of the present disclosure it is sufficient to state that all line relays are normally energized. When a train moving from left to right leaves the first passing siding to the left of the portion of track shown in the drawing, line relays H^a, H^b, H^c, etc. which govern traffic from 100 right to left are de-energized, and each relay

will remain in this condition at least until the train has passed out of the section with which such relay is associated. Similarly, when a train moving from right to left leaves the passing siding to the left of point C, relays H^6 , H^2 and H^4 etc. which govern traffic from left to right, become de-energized, and each relay will remain in this condition at least until the train passes out of the associated section. Each H relay is further controlled so that when the corresponding section becomes unoccupied the H relay for the direction in which the train is moving becomes energized. The absolute permissive block signaling system includes a stick relay designated by the reference character Q with a suitable exponent and located adjacent the right hand end of the section. A repeater relay, designated by the reference character P with an exponent corresponding to the location, is provided for each track section and is located adjacent the left hand end of the section. Referring particularly to stick relay Q^4 , this relay is provided with a pick-up circuit over which current flows from line wire 12^a , through wires 18 and 19, back contact 20 of relay R^3 , wire 21, back contact 22 of relay R^4 , wire 23, front contact 24 of relay H^4 , wire 25, winding of relay Q^4 , and wires 26 and 27 to line wire 12. This circuit is closed only when relays R^3 and R^4 are de-energized and relay H^4 is energized, as when a train moving from right to left enters section A-B. Relay H^4 will then open its front contact and interrupt the circuit just traced, but relay Q^4 will be maintained in its energized condition, as long as any part of the train occupies section A-B, by virtue of a stick circuit which may be traced from line wire 12^a , through wires 28 and 29, back contact 30 of relay R^1 , wire 31, front contact 32 of relay Q^4 , wire 33, winding of relay Q^4 , and wires 26 and 27 to line wire 12. When relay Q^4 is energized, current flows from line wire 12^a , through wires 34 and 35, front contact 36 of relay Q^4 , wire 37, winding of relay P^4 , and wires 38 and 39 to line wire 12. Relay P^4 is therefore energized only when relay Q^4 is energized.

Track circuit current is at times supplied to the primary 4 of track transformer T^1 , over a circuit which passes from line wire 12^a , through wires 28 and 40, back contact 41 of relay P^4 , wire 42, winding 4 of transformer T^1 , and wire 39 to line wire 12. This circuit is closed whenever relay P^4 is de-energized. The track transformer T^4 located at the right hand end of section A-B is supplied with track circuit current when relay Q^4 is energized, over a circuit which passes from line wire 12^a through wire 43, front contact 44 of relay Q^4 , wire 45, primary winding 4 of transformer T^4 , and wire 27 to line wire 12.

The second winding 11 of relay R^1 is con-

nected, through an impedance 15, across the rails 2 and 2^a of section A-B adjacent point A. When relay P^4 is energized, however, a path of low resistance is closed around impedance 15, which path is through wire 46, front contact 47 of relay P^4 and wire 48. When this path is closed, impedance 15 is shunted, so that winding 11 of relay R^1 is connected directly across the rails of section A-B. When relay Q^4 is de-energized, winding 11 of relay R^1 is connected across the rails of section A-B adjacent point B through back contact 49, but when relay Q^4 is energized this winding 11 is completely disconnected from the rails.

Train governing current is supplied to the track rails from the alternator K over line wires 13 and 13^a and through transformers S. For example, the circuit for transformer S^4 may be traced from line wire 13^a , through wire 50, front contact 51 of relay H^4 , wire 52, back contact 53 of relay Q^4 , wire 54, primary 7 of transformer S^4 , wire 55, back contact 56 of relay R^4 , and wire 57 to line wire 13. This circuit is closed only when relays Q^4 and R^4 are de-energized and when relay H^4 is energized. When relay P^4 is energized, and when relay H^6 is also energized, train governing current is supplied from line wire 13^a , through wire 58, front contact 59 of relay R^6 , front contact 61 of relay P^4 , wire 62, primary 7 of transformer S^1 , and wire 63 to line wire 13.

As shown in the drawing all parts of the apparatus are in their normal positions, that is, the positions corresponding to the unoccupied condition of the stretch of track here shown. The track transformer T located at the left hand end of each track section is therefore supplying track circuit current to the corresponding section, but the circuit for the track transformer located at the right hand end of each section is interrupted at a front contact of the corresponding stick relay. All track relays are energized, all line relays H are energized, and all stick relays Q and repeater relays P are de-energized. The impedance 15 associated with the track relay R at the left hand end of each section is connected in series with the corresponding relay because the low resistance path around this impedance is open, and winding 11 of the other track relay for each section is connected across the rails by the associated stick relay Q . All train governing transformers S are de-energized.

I will now assume that a train moving from left to right passes through the stretch of track shown in the drawing. As this train left the passing siding to the left of point A, line relays H^6 , H^4 and H^2 became de-energized. As the train enters section A-B, relays R^1 and R^4 become de-energized and relay H^1 also becomes de-energized. Relays Q^4 and P^4 are unaffected, but the

closing of back contact 56 of track relay R^4 completes the circuit for transformer S^4 which thereupon supplies train governing current to section A—B. As the train progresses into section B—C, relays R^3 and R^2 become de-energized and relay H^3 becomes de-energized. The closing of back contact 56 of relay R^2 completes the circuit for transformer S^3 which then supplies train governing current to section B—C, and the de-energization of relay H^3 interrupts the circuit for transformer S^4 and so discontinues the supply of train governing current to section A—B. As the rear of the train 10 passes out of section A—B relays R^1 and R^4 become energized but the remaining apparatus is unaffected. As the train passes out of section B—C relays R^3 and R^2 become energized, and as the train enters the passing siding to the right of point C the energization of relays H^6 , H^4 and H^2 returns the apparatus to its normal position.

I will now assume that a train moving from right to left passes along the track. 20 As such train left the first passing siding to the right of point C, relays H^1 , H^2 and H^5 , etc. became de-energized but the remaining apparatus remains unchanged. As the train enters section B—C it causes the de-energization of relays R^2 and R^3 . Relay H^2 also becomes de-energized, but subsequent to the de-energization of relay R^2 and prior to the opening of front contact 24 of relay H^2 the pick-up circuit for relay Q^2 is closed. The 30 relay Q^2 is subsequently held in its energized condition over its stick circuit which includes its own front contact 32 and back contact 30 of relay R^3 . The closing of front contact 36 of relay Q^2 closed the circuit for relay P^2 which thereupon closes its front contact. The opening of back contact 49 of relay Q^2 disconnects winding 11 of relay R^2 from the rails, and the closing of front contact 44 of relay Q^2 supplies alternating current 40 to the primary 4 of track transformer T^2 . Similarly, the opening of back contact 41 of relay P^2 opens the circuit for transformer T^3 , and the closing of front contact 47 of relay P^2 completes the shunt around 50 impedance 15 and connects winding 11 of relay R^3 directly to the rails of section B—C. The de-energization of relay R^2 does not complete the circuit for train governing transformer S^2 because the circuit for this 55 transformer is open at front contact 51 of relay H^5 and also at back contact 53 of relay Q^2 . The closing of front contact 61 of relay P^2 completes the circuit for primary 7 of transformer S^3 because relay H^4 is energized, and under these conditions section 60 B—C is supplied with train governing current from transformer S^3 . As the train moves through section A—B the operation of the apparatus is the same as just described 65 for section B—C. As the train moves out

of section B—C track circuit current supplied to the rails by transformer T^2 energizes relay R^3 which results in the de-energization of relay Q^2 and hence of relay P^2 . Relay R^2 is thereupon reconnected with the rails, 70 the shunt around impedance 15 for relay R^3 is opened, and transformer T^3 is energized. At the same time track transformer T^2 is de-energized. The operation of the apparatus as the train passes out of section A—B 75 will be readily understood without further explanation. When the train reaches the passing siding to the left of point A, relays H^1 , H^3 and H^5 again becomes energized to restore the apparatus to its normal condition. 80

The trackway apparatus herein shown and described is suitable for co-operation with train carried governing mechanism arranged to be responsive to train governing current in the trackway, that is, current of the frequency of alternator K. This governing mechanism is preferably arranged to give a less restrictive indication when the portion of trackway occupied by the train is being supplied with train governing current, and to display a more restrictive indication when the supply of train governing current to such portion of track is interrupted. In certain systems suitable for co-operation in this manner the train carried governing mechanism is controlled by the trackway current through the medium of suitable pick-up apparatus carried on the train in advance of the front axle. It is obvious that in systems of this character the source of train governing current must at all times be located in advance of the train, as otherwise the train governing current would be shunted away from the receiving apparatus by the 90 wheels and axles of the train itself. 95

Under certain conditions it may happen that current of train governing frequency is present in the transmission line over which track circuit current is supplied to the rails. This might result in the supply of train governing current to a section when traffic conditions in advance of a train are unsafe. It should be pointed out however, that with the apparatus shown in the drawing, the track circuit current is at all times supplied to an occupied track section by a track transformer located in the rear of the train irrespective of the direction of travel of such train. It follows that any stray train governing current present in the transmission line for generator J, or induced in any of the connections or circuits intended for track circuit current, will not be effective to produce an improper indication in the train governing mechanism for the reason that such current will be shunted away from the receiving apparatus by the wheels and axles 110 of the train. 115

Although I have herein shown and described only one form of trackway apparatus 120

embodying my invention, it is understood that various changes and modifications may be made therein within the scope of the appended claims without departing from the spirit and scope of my invention.

Having thus described my invention, what I claim is:

1. In combination, two successive sections of a railway track over which traffic moves in both directions, a first and a second transformer for each section each having a secondary winding constantly connected with the rails adjacent the left hand end of the section, a third and a fourth transformer for each section each having a secondary winding constantly connected with the rails adjacent the right hand end of the section, a first transmission line for at times supplying alternating current of one frequency to the first and third said transformers for each said section, a second transmission line for at times supplying alternating current of a different frequency to the second and fourth transformers for each said section, and means effective when either said section is occupied by a train moving toward the right and when traffic conditions in advance are safe to connect the second and third transformers of such section with their associated transmission lines, and effective when either section is occupied by a train moving toward the left and traffic conditions in advance of such train are safe to connect the first and fourth transformer for the occupied section with their corresponding transmission lines.

2. In combination, a section of railway track, a first track transformer and a first train governing transformer each having a secondary connected across the rails adjacent one end of the section, a second track transformer and a second train governing transformer each having a secondary connected across the rails adjacent the opposite end of the stretch, means for normally supplying current to the primary of the first track transformer, means effective when a train moving in one direction enters the section to supply current to the primary of the second train governing transformer, and means effective when a train moving in the opposite direction enters the section to supply current to the primaries of the second

track transformer and the first train governing transformer.

3. In combination, a section of railway track over which traffic moves in both directions, means for normally supplying track circuit current to the rails adjacent one end of the section, means effective when a train moving toward the other end of the section enters such section to supply train governing current to the rails adjacent such other end of the section, and means effective when a train moving in the opposite direction enters the section to supply train governing current to the rails adjacent said one end of the section and to supply track circuit current to the rails adjacent said other end of the section.

4. In combination, a section of railway track over which traffic moves in both directions, means for supplying track circuit current to the rails adjacent one end of the section when the section is unoccupied or when the section is occupied by a train moving toward the other end of the section, means effective when the section is occupied by a train moving in the opposite direction to supply track circuit current to the rails adjacent the other end of the section and to supply train governing current to the rails adjacent said one end of the section, and means effective when a train moving in said one direction occupies the section to supply train governing current to the rails adjacent said each other end of the section.

5. In combination, a section of railway track over which traffic moves in both directions, means for supplying track circuit current to the rails adjacent one end of the section when the section is unoccupied or is occupied by a train moving toward the other end of the section, means effective when the section is occupied by a train moving in the opposite direction for supplying track circuit current to the rails adjacent said other end of the section, and means effective when the section is occupied by a train moving in either direction for supplying train governing current to the rails in advance of such train providing traffic conditions in advance of such train are safe.

In testimony whereof I affix my signature.

ROBERT M. GILSON.

CERTIFICATE OF CORRECTION.

Patent No. 1,657,620.

Granted January 31, 1928, to

ROBERT M. GILSON.

It is hereby certified that error appears in the printed specification of the above numbered patent requiring correction as follows: Page 4, line 87, claim 4, strike out the word "each"; and that the said Letters Patent should be read with this correction therein that the same may conform to the record of the case in the Patent Office.

Signed and sealed this 21st day of February, A. D. 1928.

Seal.

M. J. Moore,
Acting Commissioner of Patents.
